UNITED STATES PATENT OFFICE.

FRANK E. THOMPSON, OF STAMFORD, CONNECTICUT, ASSIGNOR TO THE YALE & TOWNE MANUFACTURING COMPANY, OF STAMFORD, CONNECTICUT.

PIN-TUMBLER LOCK.

1,422,497.

Specification of Letters Patent. Patented July 11, 1922.

Application filed September 2, 1921. Serial No. 497,894.

To all whom it may concern:

Be it known that I, FRANK E. THOMPSON, a citizen of the United States, and a resident of Stamford, in the county of Fairfield and 5 State of Connecticut, have invented certain new and useful Improvements in Pin-Tumbler Locks; and I do hereby declare the following to be a full, clear, and exact description of the invention, such as will enable 10 others skilled in the art to which it appertains to make and use the same.

My invention relates to an improvement in cylinder locks of the pin tumbler type, and is designed particularly as an improvement 15 disclosed in U. S. Patent 874,808 granted to Warren H. Taylor, December 24th 1907.

In the Taylor lock, access to, or destruction of the pin tumbler is prevented by a 20 protecting armor located within the cylinder and the plug of the lock in advance of the pins, the armor in the plug being slotted for the passage of the key.

As the cylinder and plug are generally 25 made of comparatively soft metal, the cost of construction is considerably increased by locating the armor in the plug in line with the key slot, and the armor is necessarily weakened by such slotting.

30 The object therefore of my invention is to so locate the armor in the plug and also in the cylinder, to prevent access to the pin tumbler through an opening made by a boring tool entered through the face of the 35 lock, without necessitating any slotting of the armor, and it consists in the details of construction as will be more fully explained and pointed out in the claims.

In the accompanying drawings, Figure 1 40 is a view in elevation of the lock. Figure 2 is a view in side elevation, partly in section, the tumblers being removed and Figure 3 is a view in plan of the plug.

To prevent the possibility of access to the 45 tumbler drivers or pins in the cylinder by means of a boring tool, I provide the escutcheon or face plate 5 of the cylinder 6 with an armor consisting of two hardened steel pins 7 located immediately in front of 50 the pin chambers, the gap or space between the pins 7 being less than the diameter of the pin drivers or tumblers, and too restricted to permit of the entrance of a boring tool of sufficient size to destroy or damage the 55 drivers or pins. These hardened steel pins

7 extend from the top edge of the escutcheon or face plate 5 to the top of the plug. The plug 8, which is provided with the usual key slot 10, and which is mounted to turn in the cylinder in the well known manner, is also provided with the hardened steel pins 9 secured within holes located at opposite sides of the key slot, but within or overlapping the planes of the tumbler pins so as to prevent the possibility of the entrance of a boring tool sufficiently large to destroy the tumbler pins, and particularly those at the front. In the drawings I have shown the armor or hardened steel pins 9 located in advance of 60 the first tumbler pin and in, or overlapping 65 the plane of one side thereof and also between the first and second and second and third tumbler pins, thus absolutely protecting these pins from destruction by a boring tool entered from the front of the plug 8, 70 and other hardened pins 9' may be inserted into suitable holes in the plug so as to be disposed at an angle to the pins 9.

The armors 7 and 9 which are preferably 75 in the form of pins are secured in place in 80 the cylinder and plug respectively, and need only be wide enough, and so located to prevent a tool entered from the front plate from 85 destroying all of the tumblers or drivers, hence a tool entered from one side could not 90 be manipulated to reach all the pins, which would be necessary in order to release the plug and permit the latter to be turned to actuate the locking mechanism connected with the plug.

Having fully described my invention what I claim as new and desire to secure by Letters-Patent, is:

1. As a new article of manufacture, a tumbler lock the plug of which is provided with 95 a plurality of hardened steel pins arranged at an angle to the axis of the plug at opposite sides of the key slot and partly within the plane of the tumblers.

2. As a new article of manufacture, a pin 100 tumbler lock the plug of which is provided with a series of hardened steel pins at an angle to the axis of the plug and alternately arranged at opposite sides of the key slot 105 and partly within the planes of the holes for the pin tumblers.

3. As a new article of manufacture, a pin tumbler lock the cylinder of which is provided with a plurality of steel pins located transversely in advance of the holes 110

for the pin tumblers and drivers for the latter and in the plane of the same, and a plug having a plurality of steel pins located at an angle to the axis of the plug and at opposite sides of the key slot and partly within the planes of the holes for the pin tumblers.

4. As a new article of manufacture, a pin tumbler lock the cylinder of which is provided with a plurality of steel pins located transversely in advance of the holes for the tumblers and drivers for the latter and within the planes of said holes and a plug hav-

ing a plurality of steel pins disposed at an angle to the axis of the plug and alternately arranged at opposite sides of the key slot and partly within the planes of the holes for the pin tumblers.

In testimony whereof, I have signed this specification in the presence of two subscribing witnesses.

FRANK E. THOMPSON.
